[57] CLAIM

The ornamental design for a shoe or similar article, as shown and described.

DESCRIPTION

FIG. 1 is a top plan view of a shoe or similar article showing my new design;

FIG. 2 is a left side elevational view thereof, the right side being a mirror image thereto;

FIG. 3 is a front elevational view thereof;

FIG. 4 is a rear elevational view thereof;

FIG. 5 is an enlarged detail section of the toe insert shown in FIG. 1—3.

The characteristic feature of my design resides in the round needle point toe insert on the shoe as shown.
